MASSECUISTE TREATING APPARATUS

Samuel S. Peck, Honolulu, Territory of Hawaii

Application January 5, 1934, Serial No. 705,437

6 Claims. (Cl. 257—104)

The invention relates to the sugar industry and has special reference to the treatment of massecuite.

The principal object of the invention is to provide a device which will warm massecuite, which has already been cooled and crystallized in any form of crystallizer, to a temperature which shall reduce the viscosity sufficiently to facilitate drying in the separating or centrifugal machines. 10 It is known that different means have been resorted to for the purpose of warming massecuite for the purpose of reducing its viscosity but the great difficulty which has been experienced in existing devices lies in preventing local overheating 15 when heating water of sufficiently high temperature is used. Furthermore there have always been certain portions of the mass which do not move readily and then there usually occurs solution of some of the crystals.

20 It is with these facts in view and other contemplated improvements which will hereinafter become apparent, that I have devised the present invention which has for a very important object the provision of a massecuite treating apparatus 25 by means of which the mass may be positively and uniformly heated throughout without any danger of local overheating with the resultant disadvantages thereof, and with the assurance of positive displacement of the treated material by the 30 incoming supply, all these factors contributing to the realization of the highest degree of efficiency.

A more specific object of the invention is to provide an apparatus of this character embodying concentrically arranged rotary helical coils 35 through which circulates a constant supply of water at a desired temperature for heating the mass of massecuite to the proper degree, the rotation of the coils insuring the bringing of all portions thereof into intimate contact with all portions 40 of the mass so that the heating effect will be entirely uniform.

The invention further contemplates, under some circumstances and if such is desirable, the circulation of cold water through the coils instead of hot water though this is but a secondary object as compared with the importance of the main one.

Another object of the invention is to provide an apparatus of this character of such construction 50 and combination of parts as will permit satisfactory control of the travel of the mass through the device, this being dependent upon the head of the inflowing mass.

Yet another object is to provide an apparatus of 55 this character in which circulation of the mass

will be effected in such manner as to insure displacement of all of the treated material by the incoming new supply to avoid over-treating any portions.

An additional object is to provide an apparatus 60 of this character which will be comparatively simple and inexpensive to manufacture and assemble, easy to operate and control, positive in action, efficient and durable in service, and a general improvement in the art. 65

To the attainment of the foregoing and other objects and advantages, the invention preferably consists in the details of construction and the arrangement and combination of parts to be hereinafter more fully described and claimed, and illustrated in the accompanying drawings in which:

Figure 1 is a vertical longitudinal sectional view through the apparatus.

Figure 2 is a cross section on the line 2—2 of 75 Figure 1.

Figure 3 is a section on the line 3—3 of Figure 1.

Referring to the drawings, 1 indicates a generally cylindrical tank having an open top with 80 a discharge or outlet coupling 2 at one side and a drainage or clear out opening 3 in the bottom normally closed by a screw plug 4. The supply of massecuite or other liquid to be treated is by means of a pipe 5 located above the open top and directed downwardly and toward the vertical axis of the tank. 85

Secured to the top of tank 1 is a supporting framework comprising channel sections 10 and 11, which are secured to the side walls of the tank by brackets 12, said framework carrying a housing 13 and a bracket-like journal bearing 14. Journalized in the bracket 14 and the housing 13 is a shaft 15 adapted to be driven by any suitable transmission from a convenient source of power, said shaft having fast on the portion enclosed in the housing 13 a worm 16 which meshes with a worm wheel 17 secured upon a hollow shaft section 18 journalized in bearings in the housing 13. 95

The upper end of the shaft is connected to a swivel coupling 19 which in turn is connected with the water supply pipe 20. The lower end of the hollow shaft section 18 is closed by a plug 18'. 100

Connected to the side of the hollow shaft 18 by a horizontal pipe section 22 is a helical coil 23 which extends downwardly within the tank and is connected at its lower end, by means of a pipe section 24, with a coaxial helical coil 25, 110

the upper end of which is connected by a pipe section 26 with a centrally disposed hollow shaft 27, the upper end of which is telescopically connected with the lower end of the hollow shaft 18, 5 the lower end being journaled in a thrust bearing 28 mounted in the center of the tank bottom, said hollow shaft being equipped with a valved discharge pipe 29. The helical coils 23 and 25 are preferably of opposite pitches, so that the rotation 10 of the coils in the tank will have a certain beneficial action to be described hereinafter.

Disposed between the coils 23 and 25 is a cylindrical shell 30 open at top and bottom and into which the above mentioned feed pipe or spout 15 discharges. The shell extends the full length of the coils and terminates above the bottom of the tank. This shell is connected to the hollow shaft section 27 at the top and bottom by means of strap-like brackets 31 and 35, respectively. 20 The upper convolution of the inner helical coil 25 is attached to the upper bracket 31 by means of a strap hanger 32 and the upper convolution of the outer coil 23 is secured to the shell 30 by means of a bracket 33 and the U-bolt 34. The lower convolution of the inner helical coil 25 is connected to the lower strap-like bracket 35 by means of a suitable clamp 36. It will thus be seen that the hollow shaft sections 18 and 27, the cylindrical shell 30 and the helical coils 23 and 25 are connected rigidly together and constitute 30 a rotatory system which is actuated by the worm gearing in the housing 13.

In the operation of the apparatus, the massecuite to be treated is supplied through the feed pipe or spout 5 and passes first into the shell 30 from the bottom of which it passes upwardly into the tank 1, it being of course clear that both the shell 30 and the tank 1 will be filled. Hot water at the desired temperature is fed to the 40 coils through the pipe 20 and passes through the swivel joint 19 into the hollow shaft 18 from which it flows through the connection 22 to the upper end of the outer helical coil 23 from the lower end of which it passes through the cross connection 24 to the lower end of the inner coil 25 and then from the upper end thereof through the connection 26 into the hollow shaft 27 and out through the valved outlet pipe 29. Of course 45 it is intended that the system composed of the shell 30 and inner and outer coils together with the hollow shaft 27 be rotated and this is accomplished by means of power applied to the worm 16 which will drive the worm wheel 17 and consequently effect rotation of the hollow shaft 18 together with the coils and shell 30. 50 The rate of rotation depends upon conditions which may exist and whatever is found to be most satisfactory. As the coils are rotated and particularly by virtue of the fact that they are 55 preferably of opposite pitch, it should be clear that the entire mass of massecuite contained within the tank in passing constantly through it from the feed pipe 5 to the discharge tube will be subjected to the heating action of the water within the coils so that all portions of the mass will be effectually heated. The incoming material is of course first acted upon by the inner coil 25 and as it flows out of the bottom of the shell 30, on account of the head of the material flowing into the top of the shell it will pass out, 60 around and among the outer coils. There is consequently a constant stream of the material flowing in intimate contact with the two sets of coils or in other words a very effective circulation 65 which, combined with the movement of the coils

and their difference in pitch, will operate to insure uniform heating throughout the mass and prevent danger of localized overheating of any portions thereof. The circulation system is such that there will be no possibility of stagnation, 80 as it were, of any portions of the mass as is thought will be apparent.

While the apparatus is intended primarily for the heat treatment of massecuite it will be evident that it could also be used for cooling purposes, by the simple expedient of passing cold instead of hot water through the coils. Moreover while the device is described as particularly designed for the treatment of massecuite, yet at the same time it is easily capable of employment for treating other liquids by either heating them or cooling them, as the case may be, there being naturally no limitation as to the exact character of the material worked upon.

From the foregoing description and a study 95 of the drawings it will be apparent that I have thus provided an extremely simple and easily operated and controlled device for the purpose specified and one which will efficiently perform all the functions for which it is intended. In 100 addition, the construction involves but few parts which are simply arranged and there is consequently no likelihood of derangement so that the mechanism should have a long and satisfactory life. It is really believed from the above that 105 the construction, operation and advantages will be readily apparent to one skilled in the art without further explanation.

While I have shown and described the preferred embodiment of the invention, it should 110 be understood that the disclosure is merely an exemplification of the principles involved as the right is reserved to make all such changes in the details of construction as will widen the field of utility and increase the adaptability of the 115 device provided such changes constitute no departure from the spirit of the invention or the scope of the claims hereunto appended.

Having thus described the invention, I claim:

1. An apparatus for treating liquid material, 120 comprising a tank having an inlet at its top and also having an outlet, a rotary assembly journaled within said tank and including an inner helical coil, an outer helical coil connected in series with the inner coil, and a shell located between the inner and outer coils and terminating short of the bottom of the tank, means for rotating said assembly, and means for establishing a circulation of liquid through said coils in series.

2. An apparatus for treating viscous liquids, 130 comprising a tank having an outlet and having an inlet at its top, a rotatably driven assembly located axially within the tank and including a vertically arranged supporting shaft, a vertically extending inner helical coil surrounding said shaft, a vertically extending helical coil arranged concentrically about and spaced from said inner coil, and a cylindrical shell disposed between the inner and outer coils, the lower end of the outer coil being connected with the lower end of the inner coil, means for supplying liquid to the upper end of the outer coil, and means for discharging liquid from the upper end of the inner coil.

3. A mixing apparatus, comprising a tank, a hollow shaft rotatable therein, a shell open at top and bottom secured to said shaft, helical tubular coils of opposite pitch disposed within and without said shell and connected in contin-

uous series between the inlet and outlet ends of said shaft, and means for rotating said shaft, shell and coils.	within and without said shell and connected in series between axially disposed inlet and outlet connections, and means for rotating said shell and coils.	80
4. A mixing apparatus, comprising a tank, a hollow shaft rotatable therein and having a stop- per between its ends, fluid supply and discharge connections to the respective ends of said shaft, helical tubular coils of opposite pitch connected in series with said shaft at opposite sides of said stopper, a hollow shell carried by said shaft and interposed between said coils, and means for ro- tating said shaft, shell and coils.	6. A mixing apparatus, comprising a tank, a hollow shaft having inlet and discharge con- nections mounted in said tank and provided with a stopper intermediate its length, helical tubu- lar coils of opposite pitch disposed in axial re- lation about said shaft and connected in series with said shaft on opposite sides of said stop- per, a hollow cylindrical shell carried by said shaft and interposed between said coils, and means mounted above the tank for driving said shaft, shell and coils.	85
5. A mixing apparatus, comprising a tank having an inlet communicating with the top thereof and a discharge at a lower level, a shell open at top and bottom mounted in said tank, helical tubular coils of opposite pitch disposed		90
